UNITED STATES PATENT OFFICE.

CHARLES A. STOCKSTROM AND LOUIS STOCKSTROM, OF ST. LOUIS, MISSOURI.

DESIGN FOR A GAS OR VAPOR STOVE.

SPECIFICATION forming part of Design No. 18,258, dated April 10, 1888.

Application filed February 28, 1888. Serial No. 265,597. Term of patent 14 years.

To all whom it may concern:

Be it known that we, CHARLES A. STOCKSTROM, a citizen of the United States, and LOUIS STOCKSTROM, a subject of the Emperor of Germany, and both residents of the city of St. Louis, in the State of Missouri, have invented and produced a new and original Design for Gas or Vapor Stoves, of which the following is a specification, reference being had to the accompanying drawing, forming part thereof, which shows a perspective view of our newly-designed gas or vapor stove.

The leading feature of our design is the portion at the end of the frame at a lower elevation than the table of the latter.

1 represents the skeleton frame, and 2 the table, of a gas or vapor stove.

3 represents an end portion at a lower elevation than the table, having an opening, 4,

and spider or grating 5, surrounding the opening.

Having thus described our invention, the following is what we claim as new therein and desire to secure by Design Letters Patent:

The design for a gas or vapor stove herein described and shown, the same consisting of a skeleton frame, a table, and an end portion at a lower elevation than the table, having an opening, substantially as described.

In testimony of which invention we have hereunto set our hands this 18th day of February, 1888.

CHARLES A. STOCKSTROM.
LOUIS STOCKSTROM.

In presence of—

SAML. KNIGHT,
EDWD. S. KNIGHT.
